UNITED STATES PATENT OFFICE.

CORNELIUS T. DEMAREST, OF HACKENSACK, NEW JERSEY.

DESIGN FOR A PARING-KNIFE.

SPECIFICATION forming part of Design No. 34,565, dated May 28, 1901.

Application filed April 22, 1901. Serial No. 57,033. Term of patent 7 years.

To all whom it may concern:

Be it known that I, CORNELIUS T. DEMAREST, a citizen of the United States, and a resident of Hackensack, in the county of Bergen and State of New Jersey, have invented and produced a new and original Design for a Paring-Knife, of which the following is a full, clear, and exact description.

Reference is to be had to the accompanying drawings, forming a part of this specification, in which similar characters of reference indicate corresponding parts in all the views.

Figure 1 is a perspective view of a paring-knife, showing my design. Fig. 2 is a transverse section of the same on the line 2 2 in Fig. 1, and Fig. 3 is a like view of the same on the line 3 3 in Fig. 1.

The design in its entirety consists of a handled blade A, terminating at its front end in a point B, dished or concaved in a transverse

direction, the blade also appearing at its back edge adjacent to the said point with a second point C extending in the plane of the blade and likewise dished or concaved, but in an opposite direction to the point B.

25

The leading feature of the design consists of the blade and the two points extending therefrom and dished, as described.

Having thus fully described my invention, I claim as new and desire to secure by Letters 30 Patent—

The design for a paring-knife as herein shown and described.

In testimony whereof I have signed my name to this specification in the presence of 35 two subscribing witnesses.

CORNELIUS T. DEMAREST.
